JAMES B. LADD AND DAVID BAKER, OF PHILADELPHIA, PENNSYLVANIA, ASSIGNEES
TO LADD & BAKER, INCORPORATED, A CORPORATION OF PENNSYLVANIA.

FURNACE.

968,485.

Specification of Letters Patent. Patented Aug. 23, 1910.

Application filed December 17, 1908. Serial No. 467,951.

To all whom it may concern:

Be it known that we, JAMES B. LADD and DAVID BAKER, of Philadelphia, county of Philadelphia, and State of Pennsylvania, have invented a new and useful Improvement in Furnaces, of which the following is a specification.

This invention has reference to the treatment of ores, and refers more particularly to a furnace or kiln for treating or roasting iron pyrites, for the purpose of effectually freeing the iron of sulfur, and delivering the latter in the form of a rich sulfurous-acid gas.

The invention consists of a kiln or furnace embodying a roasting chamber in which the ore is treated, and an improved arrangement of temperature controlling flues, by means of which the degree of heat to which the ore is subjected in the roasting chamber may be nicely and accurately controlled, according to the nature of the ore being treated as regards the quantity of sulfur therein, and the changing conditions 25 which take place as the roasting operation progresses.

Referring to the drawings: Figure 1 is a side elevation of our improved furnace. Fig. 2 is a longitudinal section through the same on the line *a—a* of Fig. 3. Fig. 3 is an end elevation of the receiving end of the furnace, that into which the raw ore is delivered. Fig. 4 is a similar view of the discharge end of the furnace, that where the residue is discharged. Fig. 5 is a transverse section on the line *b—b* of Fig. 2. Fig. 6 is a longitudinal section through the nozzle and its controlling valve on an enlarged scale, showing the valve set so as to 40 permit the heated air from the annular chamber 35 to enter the nozzle and be discharged into the heating chamber. Fig. 7 is a similar view showing the valve set so as to deflect the heated air from the annular chamber and discharge it to the outside.

In the accompanying drawings: 1 represents a shell or cylinder constituting the furnace or kiln proper, which is sustained as usual at a slight inclination downward from its receiving end, and rotably supported by means of rollers 2, or by other suitable means, so that it may have im-

parted to it a slow rotary motion, conveniently by means of a drive pinion 3 engaging a rack 4 on the exterior of the cylinder, 55 this motion of the cylinder causing the ore, which is delivered into the upper receiving end, to travel slowly and uniformly to the lower delivery end, being subjected in its passage through the cylinder to a tumbling 60 or agitating action.

At its receiving end the interior of the cylinder communicates with a chamber 5 inclosed by a fixed cylindrical casing 6, formed with an upwardly extending neck 7 65 into which the raw ore is fed from a feed hopper 8 at the side of the neck, an inclined chute 9 being fixed within the chamber 5 and extending into the roasting chamber, to receive the ore from the neck and deliver 70 the same to the roasting chamber. The said neck serves also as a means for the escape of the sulfur-gases, which pass upwardly into a pipe 10 connecting with the neck, from which they may be collected for use. At 75 its delivery end the cylinder communicates with a chamber 11, inclosed by a fixed casing 12, for receiving the residue or roasted ore, which latter is discharged from the receiving chamber by means of a bell discharge valve 13.

The cylinder 1 is formed of fire-brick, in which are arranged side by side, as shown in Fig. 5, a series of longitudinal temperature controlling flues 14, 15, 16, 17, etc., certain of said flues, every alternate one as indicated by the odd numbers, being for the circulation of either air or heating gases; while the other flues are for the passage of air only, the primary purpose of this construction and arrangement being, as will be more fully described hereinafter, for the proper regulation of the temperature in the roasting chamber to meet the varying conditions encountered in the operation of the 90 furnace as regards the character of the ore being treated, etc. At its ends, the brick-work or shell of the cylinder is thickened or enlarged, the flues 14, 16, 18, etc., being deflected outwardly at the receiving end of the cylinder, and passing through the thickened portion of the same, as at *b*, whereby they will terminate in a circular line outside of and beyond the ends of the alternate

flues 15, 17, 19, etc., which latter pass straight through the thickened portion of the shell at this point. At the opposite or delivery end of the furnace, this arrangement of the flues is reversed, the flues 15, 17, 19, etc., being deflected, as at *c*, and terminating in a circular line beyond the ends of the alternate flues 14, 16, 18, etc., which latter pass straight through the thickened portion of the cylinder at this point, the purpose of which construction and relative arrangement of the flues is to enable the proper circulation of heating gases and air, as will be presently described.

15 25 represents a starting or auxiliary furnace, which communicates by a pipe 26 with an annular chamber 27 formed in the furnace casing 12, which annular chamber contains openings in its front wall adapted to 20 register with the ends of the flues 15, 17, 19, etc., the result being that as the cylinder 1 revolves, the products of combustion from the auxiliary furnace will pass into said flues, thereby heating the roasting chamber, 25 and will escape from the opposite ends of the flues into an annular chamber 28, surrounding the cylindrical casing 6 at the receiving end of the furnace, which latter chamber is inclosed by a fixed casing, and 30 contains openings in its rear wall, with which the ends of the flues 15, 17, etc., are adapted to register as the cylinder is rotated. The gases from this chamber 28 pass downwardly through an escape pipe 29 connected with the chamber, from which pipe 35 the gases pass to a stack (not shown). The purpose of this auxiliary or starting furnace is to heat the roasting chamber sufficiently to cause the ignition of the pyrites when the 40 raw ore is fed in, and inasmuch as with the ordinary commercial pyrites the temperature of combustion, after being once started, is readily maintained and without auxiliary heat, and as it frequently becomes too high, 45 thus fusing the mass of burning material and seriously retarding combustion, I propose to provide for the introduction into the flues 15, 17, etc., of cold air instead of the gases, the effect of which will be to reduce 50 the temperature and prevent a too intense combustion. The air may be introduced by any appropriate means, for instance, by the natural suction of the stack, a suitable admission opening 30 being formed in the annular chamber 27 to receive the air from the 55 outside.

As a further means for controlling the temperature in the combustion chamber, the flues 14, 16, 18, etc., are employed to reduce 60 the temperature at the receiving end of the furnace and increase it at the delivery end, by the admission into said flues of cold air at the receiving end and its discharge in heated condition, and in the form of a hot 65 blast, into the delivery end of the roasting

chamber. This is effected by means of a fan or blower 31 connected by pipe 32 with an annular chamber 33, inclosed by a suitable fixed casing 34 concentrically surrounding chamber 28, which chamber 34 has openings 70 in its rear wall adapted to register with the deflected ends of the flues 14, 16, 18, etc., into which flues the air will pass as the cylinder 1 rotates, and passing through the flues, will become heated by the heat of combustion in the roasting chamber, and will escape from the opposite ends of the flues into a chamber 35 inclosed by a fixed casing at the delivery end of the furnace, this chamber being formed in its front wall with openings 75 adapted to register with the ends of the flues. From the chamber 35 the heated air enters a nozzle 36 extending through and sustained by the casing of the chamber, and projecting downwardly and inwardly with 80 its delivery end terminating within the delivery end of the roasting chamber, by which means the heated air, in the form of a blast, will be discharged into the roasting chamber onto the ore therein. The cold air entering 85 the flues 14, 16, 18, etc., at the receiving end of the roasting chamber, has the effect of reducing the temperature at that point, where, under certain conditions it is likely to be too high, and by becoming heated by 90 this high temperature, and being introduced into the delivery end of the roasting chamber, raises the temperature at this point, where, under certain conditions, it is likely 95 to be too low.

100 It is seen, therefore, that there are embodied in the construction described, two means for controlling the temperature in the roasting chamber, one the auxiliary furnace and flues in the shell connected with 105 said furnace, which may be employed to heat up the roasting chamber or reduce the temperature therein at will, as by the banking of the fire in the auxiliary furnace and the admission of cold air into said flues; and 110 the other by means of the fan or blower connected with the alternate flues in the shell of the cylinder, the cold air passing through said flues, acting to take the heat 115 from the part of the furnace where it may be too great, and delivering the same to that part which may require a high temperature.

Under certain conditions it may not be necessary or desirable to introduce the heated air flowing through flues 14, 16, 18, etc., 120 into the roasting chamber, although it may be desirable to effect such a degree of equalization of the temperatures at the two ends of the roasting chamber as would result merely from the passage of this air through 125 the flues. Under these circumstances, the communication between the annular chamber 35 and the nozzle may be controlled by a valve 37 of such form, that the heated air 130 will be prevented from entering the roast-

ing chamber through the nozzle, and will be allowed to escape to the outside through the outer end of the nozzle. The construction of the parts whereby this result may be effected, is shown particularly in Figs. 6 and 7, where it will be seen that the annular chamber 35 communicates with the nozzle 36 by means of a number of openings extending through the wall of the chamber, 10 which openings are adapted to register with corresponding openings in a hollow valve 37 mounted in the outer end of the nozzle so as to rotate therein, in order that the openings in this valve may be brought into 15 register with the openings in the nozzle, or may be adjusted out of register, as shown in Fig. 6. The inner end of the hollow valve is conical in form, so that when the openings therein are out of register, the heated air 20 may pass from the chamber 35 into the nozzle 36. When, however, the hollow valve 37 is turned to the position shown in Fig. 7 to bring the openings therein into register with those through the walls of chamber 35, 25 the heated air from chamber 35 will flow through the registering openings and escape outwardly through the open end of the valve.

In the construction shown, particularly in Fig. 2, the rear walls of the two annular chambers 33 and 28 are disposed in a single plane transverse to the axis of rotation of the cylinder, which latter has its receiving end disposed in a similar plane and bearing 35 flatly and closely against the said walls, the abutting surfaces being of cast iron, machine-ground, and being maintained in close abutting relations, as the cylinder rotates. This construction, in connection with the 40 fact that these surfaces are extended and of considerable area by reason of the provision of two concentric annular chambers, and the thickened end of the cylinder, reduces to a minimum the liability of leakage of air 45 into the cylinder from the outside, so that there will be no danger of the dilution of the outflowing freed gases by air.

It will be understood of course that the detailed construction of our improved furnace may be variously changed and modified by the skilled mechanic without departing from the limits of my invention, provided its functions and operations are substantially as above set forth, and it is to be understood that the invention is not limited to any specific form or arrangement of the parts, except in so far as the limitations are specified in the claims.

Having thus described our invention, what we claim and desire to secure by Letters Patent of the United States is as follows:

1. In combination with a furnace having a heating chamber provided with two series of longitudinal flues surrounding the chamber, means for the independent circulation 65

and discharge of different temperature controlling mediums respectively through the two series of flues.

2. In combination with a furnace having a heating chamber provided with two series of longitudinal flues surrounding the chamber, means for circulating a temperature controlling medium through one series of flues in one direction, and means for circulating a different temperature controlling medium through the other series of flues in an opposite direction, and independently of the first controlling medium, the discharge of said controlling mediums being independent of each other. 70

3. In combination with a furnace having a heating chamber provided with two series of longitudinal flues surrounding the chamber, the individual flues of one series alternating with the individual flues of the other series, means for circulating different temperature controlling mediums through said series of flues respectively in opposite directions. 80

4. In combination with a furnace having a heating chamber provided with two series of longitudinal flues, means for circulating a heating medium through one series of flues in one direction and means for circulating an independent cooling medium in the opposite direction through the other series of flues, the discharge of the heating and cooling mediums being independent of each other. 90

5. In combination with a furnace having a heating chamber provided with longitudinal flues surrounding the same, means for introducing a cooling medium into one end of said flues and discharging the same at the opposite end of said flues into the interior of the heating chamber. 100

6. In combination with a furnace provided with a heating chamber having longitudinal flues surrounding the chamber, means for introducing a cooling medium into said flues at the receiving end of the chamber and discharging the same into the delivery end of the heating chamber. 110

7. In combination with a furnace having a heating chamber provided with longitudinal flues surrounding the same, means for introducing cold air into the flues at the receiving end of the heating chamber, and a nozzle communicating with the opposite ends of the flues and arranged to deliver the heated air into the interior of the heating chamber at its delivery end. 115

8. In combination with a furnace provided with a heating chamber to receive the raw ore at one end and discharge the residue at the opposite end, and having two series of longitudinal flues surrounding the chamber side by side and terminating at their opposite ends respectively in two different circular planes, means for the intro- 125

duction of cold air into one series of flues at the receiving end of the furnace, means whereby the air discharged from the opposite ends of said flues may be introduced 5 into the heating chamber, and means for introducing heating gases into the ends of the other series of flues at the discharging end of the furnace.

9. In combination with a furnace provided with a heating chamber to receive the raw ore at one end and discharge the residue at the other end, and having two series of longitudinal surrounding flues, means for the introduction of cold air into one series 15 of flues at the receiving end of the furnace, means whereby the air discharged from the opposite ends of said flues may be introduced into the heating chamber, and means for introducing heating gases into the ends of the other series of flues at the discharging end 20 of the furnace.

10. In combination with a furnace having a heating chamber provided with surrounding longitudinal flues, means for the introduction of air into said flues at the receiving end of the furnace, means whereby the air issuing from the opposite end of the said flues may be discharged into the heating chamber, and means for deflecting the air in 25 its passage to the heating chamber and discharging the same to the outside.

11. In combination with a furnace having a cylindrical rotating heating chamber provided with surrounding flues, means for the introduction of cold air into the ends of the flues at the receiving end of the furnace, a nozzle connected with the opposite ends of 35 said flues and arranged to direct the air into the heating chamber, and a valve for controlling the flow of the air through the nozzle.

12. A furnace having a cylindrical rotary heating chamber provided with two series of flues having their ends at one end of the furnace terminating respectively in different 45 circular concentric lines.

13. A furnace having a cylindrical rotary heating chamber provided with longitudinal surrounding flues disposed in a circular field 50 at a point between the ends of the furnace and terminating at the ends of the furnace respectively in different circular concentric lines.

14. A furnace having a cylindrical rotary heating chamber provided with two series of longitudinal flues surrounding the chamber, with the flues of one series alternating with those of the other, the flues of one series terminating at the end of the furnace 60 in one circular line and the flues of the other series terminating at the same end of the furnace in a different circular line concentric with the first.

15. A furnace provided with a rotary cylindrical heating chamber having longitudi-

nal flues surrounding the chamber side by side and terminating at opposite ends in circular lines extending respectively different distances from the center of rotation.

16. A furnace having a rotary cylindrical heating chamber provided with two series of flues extending longitudinally and surrounding the chamber, one series of flues being deflected at one end outwardly and the other series of flues being deflected at the 75 opposite end outwardly.

17. In combination with a furnace having a heating chamber provided with surrounding longitudinal flues, means for circulating a heating medium through said flues to start 80 combustion in the heating chamber, and means for admitting at will a cooling medium into the same flues to retard combustion.

18. In combination with a furnace provided with a heating chamber having surrounding longitudinally extending flues, means for circulating either air or heating gases in one direction through certain of 85 said flues, and means for circulating cold air in the opposite direction through the other flues.

19. In combination with a furnace provided with a heating chamber having surrounding heating flues, an auxiliary furnace 90 and connections between the auxiliary furnace and heating flues to deliver the products of combustion to said flues.

20. In combination with a furnace provided with a rotary cylindrical heating chamber having two series of surrounding longitudinal flues arranged side by side with the opposite ends of the flues of one series terminating respectively in lines concentric with but different from the lines in which 100 the opposite ends of the other series of flues respectively terminate, the said furnace having two fixed chambers at one end with which the two series of flues respectively communicate at that end, and having at the 105 opposite end two fixed chambers with which the two series of flues respectively communicate at that end.

21. A furnace provided with a cylindrical rotary heating chamber having two series 110 of surrounding longitudinal flues, the said furnace being further provided at each end with two chambers communicating respectively with said series of flues.

22. In combination with a furnace having 115 a rotary cylindrical heating chamber formed with two series of longitudinal flues extending side by side and surrounding said chamber, an air blower connected with the ends of the flues of one series at the receiving end 120 of the furnace, means at the opposite ends of said flues for directing the air from the blower into the interior of the heating chamber at its delivery end, and an auxiliary 125 furnace connected with the ends of the other 130

series of flues at the delivery end of the furnaces, the opposite ends of said last named series of flues being arranged to discharge the products of combustion passing 5 through them from the auxiliary furnace.

23. In a furnace the combination with a fixed casing at the receiving end formed with an annular chamber having its rear wall disposed in a plane transverse to the 10 axis of the chamber, of a horizontal rotary cylinder constituting a heating chamber and formed with longitudinal surrounding flues adapted to communicate with the annular chamber, the end of said cylinder being

formed to abut flatly and closely against the 15 wall of the annular chamber; whereby the leakage of air into the heating chamber will be prevented.

In testimony whereof we hereunto set our hands this twenty-fifth day of November, 20 1908, in the presence of two attesting witnesses.
